FIG. 1 is a front, right perspective view of a light and optic mount for a firearm showing our new design;

FIG. 2 is a back, right perspective view of the light and optic mount for a firearm of FIG. 1;

FIG. 3 is a front elevation view of the light and optic mount for a firearm of FIG. 1;

FIG. 4 is a back elevation view of the light and optic mount for a firearm of FIG. 1;

FIG. 5 is a right elevation view of the light and optic mount for a firearm of FIG. 1;

FIG. 6 is a left elevation view of the light and optic mount for a firearm of FIG. 1;

FIG. 7 is a top plan view of the light and optic mount for a firearm of FIG. 1; and,

FIG. 8 is a bottom plan view of the light and optic mount for a firearm of FIG. 1.

The broken lines (where present) in all figures illustrate portions of the light and optic mount for a firearm that form no part of the claimed design.

1 Claim, 5 Drawing Sheets
